METHOD OF MAKING VENEERED DOORS, PANELS AND THE LIKE

Application filed April 13, 1931. Serial No. 539,774.

In veneering moldings, panels, and other products, wherein the core member thereof to be veneered has steps or other facial irregularities, it has been common practice, for 5 the want of a commercially practical alternative, to veneer only flat and easily covered front facial portions of the core, leaving projecting, angular, and other core faces more difficult to cover exposed because of the 10 ability to bend the veneer to form sharp corners without rupture. This required the exposed core portions to be constructed of select and often high-priced material that the unveneered portions thereof would match 15 the veneered portions and be acceptable to the trade. In cases where ornamental veneer having irregular grain was used, a perfect match could not be had with the straight grain of the unveneered core portions, and 20 often the high cost of constructing the exposed core part of the same material as the veneer, necessitated the substitution of less expensive and less satisfactory woods to form the exposed core parts.

25 It is an object of this invention to overcome these difficulties and to enable the manufacture of a superior all over veneered product in a commercially practical and economical manner, producing a product having 30 many of the characteristics of a monolithic structure, free from the usual wood troubles such as swelling and shrinking with humidity and temperature changes, and one having a durable and permanent finish obtained during the process of manufacture.

Reference will be had to the accompanying drawings which form a part of this specification, and wherein like reference characters designate corresponding parts throughout the several views, wherein:

Fig. 1 is a view in front elevation of a product of the invention, namely a finished door with parts broken away to expose the core.

Fig. 2 is a view in front elevation of a 45 stile and fragments of the top and bottom rails of the core juxtaposed for assembly.

Fig. 3 is a transverse vertical sectional view, through the dies, core and veneer layers, the latter being juxtaposed ready for assembly, and this view may also be read as a

longitudinal vertical sectional view of the same.

Fig. 4 is an enlarged detailed vertical sectional view through a fragment of the core and veneer layers prior to compression by 55 the die.

Fig. 5 is a similar view of the same after compression, the die being fragmentally included in the illustration.

Figs. 6, 7 and 8 are corresponding transverse vertical sectional views of the central core panel with veneer layers applied, illustrating various ways of joining sections of the outer veneer layer when the latter is composed of sections, and,

Fig. 9 is a transverse sectional view through a strip of stile and molding (or rail and molding) stock prior to the molding being shaped.

Referring to the drawings, reference 70 numeral 15 designates the side stiles, 16 and 17 the respective top and bottom rails, 18 the mitered molding, and 19 the filling or central panel of a core to be veneered. The stiles and rails may each be of usual solid or composite 75 structure though preferably of comparatively compressible, soft, light and inexpensive woods, as pine; the molding is of less expensive and comparatively incompressible and harder wood, as birch; and the central core panel 19 is of soft, light compressible wood, as basswood or poplar. Other woods or materials having the desired characteristics may be used.

Departing from the usual method of constructing door and other panel cores, the moldings 18 are unformed when applied to the stiles and rails, that is, referring to Fig. 9, the molding stock 18^a thicker than the stile 15, (or than a rail as the case may be), is 80 glued at its edge to the edge of the stile, and the united strips are then passed through a molding forming machine, and the molding stock 18^a given the cross sectional shape of the finished molding 18, and if desired the 85 stile (or rail) stock reduced to proper thickness.

The stile moldings are then mitered at 20, the ends 18^b being removed and discarded, (see Fig. 2), and the dowel holes 21 bored 100

in the stile edge, originally occupied by the discarded molding ends 18^b, ready to receive the dowel pins 22 located in the ends of the rails 16 and 17. The moldings 18 of the rails 5 are co-extensive therewith and are merely mitered as at 20 at their ends, and the stiles 15 and the rails 16 and 17 with their attached moldings 18 are then assembled into a core frame. The central core-panel 19 is then cut 10 to snugly fit within and fill the central opening of the frame, its edges abutting those of the molding 18 and being held in place frictionally or at least without permanent fixture.

15 Annular products, instead of the rectangular one illustrated may be produced by following the general steps of this method, in which case the surrounding core frame will be made up of jointed pieces corresponding to the jointed pieces 15, 16 and 17 20 with attached moldings 18, and the frame opening closed by a circular core panel corresponding to the core 19.

In constructing veneered doors and panels 25 showing a stepped molding between the stile and rails and the central core panel, the practice has been to only veneer the flat faces of the stile and rails and of the central core panel, leaving the molding unveneered because of the difficulties encountered in forcing the veneer without rupture into the corners of the pressing die 24, the latter being essential to the production of sharp, well defined and uniform corners on the final product.

In overcoming this great difficulty, each molding 18 adjacent points where steps or angles would ordinarily occur (as between the faces of the molding itself, or between the 40 faces of the molding and the faces of the central core panel 19 or the surrounding frame which is made up by the jointing of the stiles 15 to the rails 16 and 17), beads 25 are provided to force the veneering into the 45 corners 24^a of the die and compel the veneer to accurately and completely conform itself to the angles of the die corners 24^b. These die corners are very slightly nosed off or filleted, but still of such a nature that the 50 veneer would not conform itself to them without provision of some special means such as the beads 25 to compel the veneer to shape itself exactly to the contour of the faces of the die 24.

55 The veneer may consist of a single thin layer of ornamental wood, or of suitable paper or the like, but in many cases better results can be obtained by employing one or more backing layers. In the example, an ornamental wood outer veneer layer 30 of approximately 1/100 of an inch thickness is employed; backed by padding and bonding 60 layers 31, 32, 33 and 34. The layers 31 and 32 are preferably of paper, and the layers 33 and 34 preferably of cheap and comparative-

ly thick wood veneer, though all paper or all wood may be used for these layers 31 to 34 and the arrangement modified. The grain of the layer 34 crosses that of the general grain of the core, and the grain of the layer 33 crosses that of the layer 34. All padding and bonding layers should be laid with their grains crossed, and when the grain of the ornamental outer layer runs with that of the next wood layer, one or more layers of paper may be employed between them, but the outer veneer layer is so thin that it is immaterial if its grain should run with that of an adjacent wood layer.

70 Various adhesives may be used in assembling the different parts of the product. Synthetic resin adhesive, alcohol soluble (as bakelite) or water soluble (now obtainable) may be used, and are herein adopted since the desired results can only be obtained through the use of an adhesive that will first fuse and then become infusible and insoluble (at least under ordinary household conditions or the like) after being subjected to pressure under a heated die.

75 In applying the veneering to the core, the latter first receives a coat of one of the named synthetic resin adhesives, the layers or sheets 34 and 35 are similarly coated on both sides and laid upon the core with the grains of contacting layers and core crossed. The paper sheets 31 and 32 are similarly coated on both sides and then laid upon the others, and the ornamental veneer layer 30 coated on both sides finally laid onto the pack. Brush coating

may be practiced, but better results are obtainable in the product by dipping the various veneer layers 30 to 34 in a vat of adhesive so the same will become thoroughly saturated. The water soluble adhesive described, 105 being cheaper than the alcohol soluble adhesive, may be used wherever desirable, but for the outer layer it is preferable to coat the same by dipping it in a vat of an alcohol soluble adhesive, such as bakelite, since that material after being subjected to treatment under the die leaves a smooth varnish-like exterior finish, occurring during the process of manufacturing the door, and making it unnecessary to subject the door or panel to any painting, varnishing or finishing operation after its delivery to the place of use. The adhesive applied to the outer veneer

layer 30, or one in the same category, is obtainable in a variety of colors or may be colored, hence almost any color effect is obtainable. Satisfactory results can be obtained with the water soluble synthetic resin adhesive for many purposes, but in its present state of perfection, the alcohol soluble adhesive mentioned is preferable in treating the outer veneer layer 30.

110 By giving the die 24 a polished face, the outer coating of the veneer layer 30 will be produced with a polished surface, or by

scratching the die face, the coating will partake of a scratched or dull finish. There is nothing about the nature of the varnish-like coating to prevent subsequent decoration, as 5 by painting, after delivery from the dies, but if any objection occurs from this source, the outer veneer is left in its native state and no adhesive is applied thereto since the underlying layer 31 supplies sufficient adhesive.

- 10 Upon being subjected to pressure under the die 24, the stack of veneer layers is forced toward and against the core until the inner veneer layer 34 contacts therewith. The die 24 being heated by fluid, such as steam, flowing 15 through the passage 40 in the platen 41, fuses the adhesive and causes the same to change toward the infusible and insoluble state, and after a required period, the die is cooled by running a cooling medium, such as 20 cold water through the passages 40, after which the product is removed.

If both faces of the core are to be veneered, the general method is the same, except that the veneering pack is stacked on the lower 25 die 24, the core placed on the pack, the other veneer pack placed on the core, and the other die 24 laid onto the upper veneer stack.

Were the beads 25 not present, the veneer would not enter the corners 24a or properly 30 turn the corners 24b of the die, and as a result a very imperfect and unacceptable product would be formed. Since the beads 25 are a part of the comparatively hard wood molding strip 18, though the same could be 35 separately applied thereto, the beads offer the necessary resistance to the veneer pack as will cause the outer veneer layer 30 to fill and completely conform to the contour of the die 24. In addition to the beads 25 being 40 required to offer this essential resistance, the same must be compressible and deformable, one or both, whether compression and deformation of the beads are confined to that member or imparted to the molding strip on which 45 it is provided.

At or adjacent the corners, where the beads 25 occur, the various layers of veneer, whether one or more, are highly compressed, so that in addition to the outer veneer layer 30 50 being completely forced into the die corners, such corners become highly compressed and compacted offering dense sharp corners in the product not easily dented. The beads themselves under the high pressure to which the 55 die is subjected, flatten out somewhat as in Fig. 5, though the exact form of deformation varies according to conditions. Sometimes a bead is forced more into the molding strip 18, while at other times it is spread more or 60 less laterally over and onto and even into the adjacent faces 15^a, 18^a or 18^a and 18^b, and other faces of the molding, as well as the face of the core panel 19.

By this method of constructing a door or 65 other panel, as is obvious, there may be sur-

face irregularities in the core, the joints may be open between the various core parts, the parts of the core loosely assembled and even unaffixed to each other, and because of the veneer sheets or layers crossing the various 70 joints and the surplus of adhesive entering any open joints or cracks in the core or veneering the product will be bonded into virtually a monolithic mass.

The saturated padding and bonding layers 75 when subjected to heat and pressure, form a plastic backing mass, conforming itself to the irregularities in the core, and which change shape to permit the outer veneer layer to conform to the irregularities in the die without becoming ruptured. Should any rupture of a slight nature occur, the saturated condition of the outer veneer layer 30 and the underlying layers will afford a sufficient quantity 80 of the adhesive to fill the voids in the rupture, and where an outer surface coating for outer veneer layer 31 is intended, the filled fracture 85 will not be materially noticeable to the eye if at all. In cases where the outer surface of the veneer layer 30 is uncoated, the filling of the voids of the rupture will make filling of the voids by putty unnecessary after completion of the product.

It is not essential that the beads be provided all on one strip 18 as in the example. 90 They may be provided on either of two adjoining portions that form a step or corner, though in the example the beads 25 are all provided or formed on the molding strip 18 since, because of that strip being of harder 95 material than the adjacent parts and affording the required resistance to compression, the adjoining parts may be made of cheaper material and at the same time possess the desired 100 compressibility essential to the production of 105 a perfectly and satisfactorily allover veneered product.

By this method, where a veneer layer, such 110 as the outer one 30, because of its size, must be built in sections, the sections may be abutted as in Fig. 6; or abutted and taped at 30^a as in Fig. 7, in which case the plasticity of 115 the underlying veneer layers will cause them to give and compress to accommodate the tape; or as in Fig. 8, the adjoining sections of the outer veneer layer 30 may be overlapped, in which case the plasticity of the underlying layers will compensate for the added thickness. The possibility of lapping 120 the sections of the outer veneer layer 30 to form an acceptable joint while within the die is a great advancement in the art, and greatly facilitates manufacture in that it eliminates taping outside the die or careful abutting of 125 the outer veneer layer sections while within the die, as well as the necessary straightening of the edges of the sections to permitting abutting of such edges. In the lapped joint 130 of Fig. 8, the outer surfaces of the veneer sections occupy the same plane and the edge of

the underlapped portion 30^b is provided for by the compacting of the underlying padding layers and the core panel 19, as well as the compacting of the sections of the outer veneer layer. When lapped, the edges of the sections of the veneer outer layer 30 may be irregular since the sections are merged under the high compression and if any void should occur in the joint, it is filled by the adhesive 10 and rendered virtually unnoticeable if noticeable at all.

The invention is practised generally with very thin veneers, at times as thin as 1/100" and when employing the overlapping seam of 15 Fig. 8, the thickness of the sections of veneer 30 cannot successfully exceed 1/80" in thickness, and even when using the seam of Fig. 7 which involves the same principles of Fig. 8, the thickness of the veneer sections should not 20 exceed 1/80" in thickness, since if a greater thickness is used a distinct line will show and the seam will be so elevated that the panel would have to be rejected or subjected to an extremely expensive refinishing operation.

25 The entire interior structure of the door may be very imperfect; joints may be open, surfaces irregular, and cracks and checks present, since under the high pressure of the die all interior portions of the structure beneath the outer surface of the outer veneer layer 30 are compressed and deformed wherever necessary in order that the outer face of the veneer layer 30 should conform perfectly to the contour of the die.

25 Certain panels may not require the presence of the molding 18, in which case the central core panel 19 would join the stile 15 and rails 16 and 17 without permanent fixture, but a step would be present necessitating a 10 bead 25 on either the stile 15 and rail 16 and 17 or on the central core panel 19 (the former being preferable), to cause the veneer layer 30 to be fully pressed into the corners of the die 24.

35 Particular attention is directed to the fact that in dipping or brush coating the various veneer layers and core parts, the adhesive will virtually entirely penetrate some or all of the veneer layers and will penetrate into the core parts sufficiently to cause the compressed and deformed portions of the veneer layers and core parts to retain their compressed and deformed condition after removal of the veneered product from the dies; this retention of compression and deformation being due to the hardening of the synthetic resin adhesive, while the product is maintained under the pressure of the dies. Attention is further directed to the fact that because the adhesive used is unaffected by humidity and temperature changes, or by ordinary solvents, it will prevent swelling, shrinking, conflagration, or separation of the component parts of any veneered product constructed in accordance with the provisions of this method.

The synthetic resin, after the veneer and core parts have been treated therewith is permitted to harden to a non-flowing state, and when under the pressure of the heated die, the adhesive first becomes soft and flowing 70 and later hard and non-flowing condition before the product is removed from the dies.

Attention is directed to the fact that without the veneer layers 30 to 34, or at least one of them, crossing the miters 20 as well as the other joints, between the various parts, light 75 would show through these joints and one could look through them, since no matter how carefully the miters 20 and other joints may be fitted they would soon open producing 80 material cracks.

It is further pointed out that the stiles 15 and rails 16 and moldings 25 could not be formed integrally out of the same piece of stock since it is essential that the moldings 18 be of fairly hard wood such as birch with little compressibility while it is desirable that the stiles 15 and rails 16 be of compressible softer wood such as pine permitting scrap lumber to be used. Also the stiles 15 and rails 16 being of less thickness than the moldings 18, it would be a worthless waste to cut the stiles and rails down from stock as thick as that 18a required for the moldings 18. Further since the stiles and rails for these 90 reasons cannot be made integrally, difficulties encountered in centering and attaching irregular preformed moldings 18 by their edges to the stiles 15 and rails 16 is avoided by the 95 simpler time and expense reducing method of first attaching regular molding stock 18a to the stiles 15 and rails 16 and then forming the latter into molding.

100 What is claimed is:—

1. The method of making a panel, consisting in attaching unformed molding stock to the stiles and rails, then transforming the molding stock into molding, mitering the stile moldings short of the stile ends and removing the molding ends beyond the miters to permit the ends of the rails to join directly with the stiles, joining the rails and stiles with their molding miters matching to form a frame, providing a filling for the frame center, and affixing a veneer layer to one face of the frame, moldings, and filling and across joints therebetween.

2. The method of making a veneered panel, consisting in attaching thicker unformed molding stock to the stiles and rails of a core, then transforming the molding stock into molding thicker than the stiles and rails, mitering the stile moldings short of the stile ends and removing the molding ends beyond 110 the miters to permit the ends of the rails to join directly with the stiles, joining the rails and stiles with their attached mitered moldings to form a frame, providing a filling for the frame center, and affixing a veneer layer 115 120 125 130

to one face of the frame, moldings and filling and across joints therebetween.

3. The method of making a veneered panel, consisting in attaching unformed molding stock having substantially the density of birch to less dense stiles and rails of a core, then transforming the molding stock into molding having portions of less thickness than the stiles, mitering the stile ends and removing the molding ends beyond the miters to permit the ends of the rails to join directly with the stiles, joining the rails and stiles with their attached mitered moldings to form a frame, providing a filling of less thickness than the moldings for the frame center, and affixing a veneer layer to one face of the frame, moldings and filling and across joints therebetween.

4. The method of causing veneer applied to two angularly related surfaces of a core to fill the apex of an angle formed by two correspondingly related angular surfaces of a pressing die; consisting in providing the core, adjacent the juncture of its angularly related surfaces, with a compressible projection that extends beyond one face of one of its said surfaces; placing veneer between said die and core; and subjecting the core and veneer to pressure, thereby causing the projection to force the veneer into the angle of the die and also causing the projection to be compressed.

5. The method of causing veneer applied to two angularly related surfaces of a compressible core to conform to the apex of an angle formed by two correspondingly related angular surfaces of a pressing die; consisting in providing the core, adjacent the juncture of its angularly related surfaces; with a projection that extends beyond one face of one of its said surfaces; placing veneer between said die and core; and subjecting the core and veneer to pressure, thereby causing the projection to force the veneer into the angle of the die and itself to be forced into the compressible core.

6. The method of causing veneer applied to two angularly related surfaces of a core to fill the apex of an angle formed by two correspondingly related angular surfaces of a pressing die; consisting in providing the core, adjacent the juncture of its angularly related surfaces, with a deformable projection that extends beyond one face of one of its said surfaces; placing veneer between said die and core; and subjecting the core and veneer to pressure, thereby causing the projection to force the veneer into the angle of the die and also causing the projection to be deformed.

7. The method of causing veneer applied to two angularly related surfaces of a compressible core to fill the apex of an angle formed by two correspondingly related angular surfaces of a pressing die; consisting in providing the core, adjacent the juncture of its angularly related surfaces, with a deformable projec-

tion that extends beyond one face of one of its said surfaces; placing veneer between said die and core; and subjecting the core and veneer to pressure sufficient to deform and force said projection into the compressible core.

8. The method of veneering an irregularly faced core, consisting in providing a core of parts which produce a step where their edges adjoin, providing a compressible projection on one of said parts adjacent its edge and which projection extends beyond its face and that of the adjoining part, placing veneer in juxtaposition to said core parts, forcing the veneer by means of a stepped face die against the core parts with sufficient pressure to deform the projection after the latter has forced the veneer completely into the corners of the die face.

9. The method of veneering a stepped core by means of a die having a stepped face, consisting in providing a compressible projection on the core adjacent the step thereof, placing veneer in the presence of adhesive in position to be applied, moving the die and core relatively to cause the projection to engage the veneer and force the same into the corners in the die face and thereafter to cause the projection and veneer to become compressed sufficiently to permit the main body of the veneer to engage the main faces of the core throughout.

10. The method of veneering a stepped core by means of a die having a stepped face, consisting in providing a compressible projection on the core adjacent the step thereof, placing a layer of veneer and a padding layer therefor in the presence of adhesive in position to be applied, moving the die and core relatively to cause the projection to engage the padding and force the same and the veneer to conform to the step in the die and thereafter to cause the projection, veneer and padding to become compressed sufficiently to cause a dense corner to be formed in the product and the main body of the veneer to engage the main faces of the core throughout.

11. The method of forming a veneered product, consisting in providing a foundation with a projection, forcing veneer against the foundation by means of a die having a facial irregularity, and in the presence of a synthetic resin adhesive whereby the projection will first force the veneer into the irregularity of the die and will then be compressed, and in applying heat sufficient to transform the synthetic resin adhesive into a hard moisture-proof substance capable of maintaining the projection in its compressed state when the product is subjected to moist atmosphere.

12. The method of veneering a compressible foundation, consisting in placing a layer of wood veneer composed of sections not exceeding $1/80''$ in thickness upon a compressible non-elastic foundation and with an

- edge portion of one veneer section underlapping that of the other section, applying an adhesive to be present between the veneer and foundation, and applying pressure and causing the outer faces of the veneer sections without subsequent treatment to assume a common plane and the edge portion of the underlapped section to be forced into the foundation.
- 10 13. The method of making a finished, externally coated, jointed-veneer faced article; consisting in placing upon a compressible non-elastic foundation sections of wood veneer having thickness not exceeding 1/80 of an inch and having an edge portion of one veneer section underlapping that of the other veneer section, providing synthetic resin upon the external faces of the veneer sections and between the veneer sections and the foundation, applying pressure and causing the outer faces of the veneer sections without subsequent treatment to assume a common plane and the edge portion of the underlapped veneer section to be forced into the foundation, and reacting the synthetic resin to maintain the parts in the relation to which they are pressed.
- 15 20 25
